UNITED STATES PATENT OFFICE.

JOHN C. ST. JOHN, OF BOSTON, MASSACHUSETTS, ASSIGNOR OF ONE-THIRD
TO CHARLES A. RICHARDSON, OF SAME PLACE.

PICK-KEY FOR ZITHERS.

SPECIFICATION forming part of Letters Patent No. 678,140, dated July 9, 1901.

Application filed August 18, 1900. Serial No. 27,253. (No model.)

To all whom it may concern:

Be it known that I, JOHN C. ST. JOHN, a citizen of the United States, and a resident of Boston, in the county of Suffolk and State of Massachusetts, have invented an Improvement in Pick-Keys for Zithers, &c., of which the following description, in connection with the accompanying drawings, is a specification, like letters on the drawings representing like parts.

My invention is an improvement in stringed instruments, being particularly adapted to zithers, autoharps, and the like; and it has for its object the provision of a plectrum or pick-key capable of giving a comparatively rigid and firm pick to the string and also preferably simultaneously operating a cushion or damper arranged to coöperate with the various fine and coarse strings of the usual instrument. The requirements of a musical instrument of this character are exceedingly delicate and difficult to meet for the best results—as, for instance, the strings are of different sizes, and while they should be theoretically level, yet in practice they are uneven, so that it is difficult to get a damper which will act uniformly on these uneven strings, and, moreover, it is desirable that the damper should remain in damping contact with all the strings excepting those which are being picked and that the damper should be actuated directly by the movement of the pick-key and be directly responsive thereto. The parts also of the damper and its actuator and the pick-actuating mechanism should be compact and incapable of any clicking, rattling, scraping, or other sound, while at the same time being long-lived under more or less rough usage.

In its preferred form the pick itself is formed as a separate part from the carrier and actuator thereof, being mounted loosely between two post-like parts guided in a vertical movement by any suitable sustaining device and held toward each other and normally in raised position by a spring, the result being that the pick proper is pinched or retarded by the frictional engagement on its opposite sides of the adjacent ends of the post-like members, so that while it is free to be

swung by contact with the cam-surfaces referred to it is prevented by this frictional retardation from swinging any farther than it should be swung.

Stated in general terms, my invention comprises the provision of a comparatively rigid pick capable of free up-and-down movement and mounted adjacent to a cam-surface by means of which the pick, while free to engage a string in its downward movement, is turned to one side or deflected away from said string while moving up past the string again, and then engages another cam-surface which restores the pick to its normal picking position, the key which carries said pick being provided with a pressure device or damper-actuator coöperating with a yielding or distensible and compressible cushion extending transversely between the strings of the instrument in position to be engaged by any one of the several keys of the instrument.

Further advantages and the preferred embodiment of my invention will be set forth in detail in the following description, reference being had to the accompanying drawings, and the invention will be more particularly defined in the appended claims, forming a part of this specification.

In the drawings, Figure 1 is a fragmentary view of any suitable stringed instrument, showing a sufficient portion thereof with my invention applied thereto to enable the latter to be understood. Fig. 2 is a transverse view taken on the line 2 2, Fig. 1, showing the details of my invention greatly enlarged. Fig. 3 is a central longitudinal sectional view on the line 3 3, Fig. 1, the parts being broken away for clearness of illustration, this figure, however, showing the parts in the relative positions when the pick has been operated and is in its most depressed position, whereas Fig. 2 shows the parts in their normal position before being operated. Fig. 4 is a horizontal transverse section taken on the line 4 4, Fig. 2, this figure also indicating in dotted lines the position assumed by the pick when depressed. Fig. 5 is a perspective view of the pick proper.

It will be understood that the keyboard A and arrangement and kind of strings a may

be of any usual or preferred kind which it is desired to play or provide with pick-keys and a damper. Various kinds of devices of this general character have already been provided, 5 most of them being more or less complicated and all of them, so far as I am aware, being quite liable to get out of order because of the frailty of the parts or yielding character and complicated arrangement thereof, and therefore I wish to direct attention at the beginning to the simplicity of construction, durability, and comparative rigidity of the parts of my invention and also to the facility with which any one portion thereof, if worn, may 10 be replaced. The keys K are mounted in or on the frame of the instrument or secured in position in any suitable manner, being herein shown as supported in a keyboard A, and in the preferred embodiment, as herein shown, 15 comprise a tubular support k, although not restricted thereto, said support acting as a guide for the plunger-like device, herein shown as consisting of a lower part or post-like member k' and an upper part k², provided with a finger-rest or thumb-piece k³ and a pick proper, k⁴, mounted between the adjacent ends of the parts k' and k². The pick proper is shown in Fig. 5, where it will be seen to comprise a tongue, of metal or other suitable substance, rigidly secured to a pin k⁵, which projects above and below the tongue or pick proper, the latter being preferably upturned at its end k⁶ to constitute a picking-lip adapted to give the best effects as it picks the string. 20 The projecting ends of the pin k⁵ are mounted in suitable holes or recesses provided therefor in the adjacent ends of the members k' and k², thus constituting one convenient means for mounting the pick in position, although 25 I am not restricted thereto, nor, in fact, to any of the other details herein specifically set forth otherwise than as expressed in the claims. The movable parts already mentioned are held normally in raised position by 30 a spring k⁶, which bears against the lower end of the part k' and against a plug or any other retaining means k⁷ at the lower end of the key. The part k² of the key is held against rotation by a depending arm or damper-actuator k⁸, fastened at one end to the thumb-piece k³ and in sliding engagement in the projecting ear k⁹, against the lower side of which is adapted to contact a stop k¹⁰, said stop preferably consisting of a piece of felt secured in a notch k¹¹ in the damper-actuator. 35 The lower end of the actuator k⁸ is laterally extended, as indicated at k¹², and extends substantially at right angles to the normal position of the pick k⁴, in position to engage a damper k¹³. Said damper is herein shown as 40 consisting of a hollow member or tube, which may be made of rubber or any other material capable of being compressed and extended and resilient either because of the material or contained air or other means, said tube extending across the keyboard beneath the keys.

The damper k¹³ is of a yielding nature, such that if one string should be slightly lower than the adjacent strings the damper will yield to whatever position the said string or any other strings may be in, thereby bringing substantially the same damping pressure on all the respective strings, while at the same time being capable of being instantly depressed at any point by any key which may be operated, the operation being clearly indicated in Fig. 3.

Viewing Fig. 2, it will be seen that the pick or plectrum k⁴ extends out through an aperture in the guide k, said aperture preferably having a curved or cut-out portion k¹⁴, the lower curve thereof, k¹⁵, coming substantially in line with the vertical descending movement of the pick. The purpose of these two portions of the opening is to enable the pick k⁴ to descend in its picking movement without sliding contact with any part, but simply passing freely from its upper position until it strikes the slanting surface k¹⁵, and this surface is made quite steep or is given an easy slant in order that there may be no sound produced by the striking against the same of the pick. Below the point k¹⁵ is a cam-surface k¹⁶, which serves to deflect the pick k⁴ from the full-line position, Fig. 4, to the dotted-line position, thereby turning said pick entirely out of any possible engagement with the string as the pick rises after having been depressed. Above the cam-surface k¹⁶ is a substantially similar cam-surface k¹⁷, extending approximately parallel to the surface k¹⁶ and operating in the same manner, but in a reverse direction, these two cam-surfaces serving to turn the pick on its pivot first to the left, Fig. 4, away from the string, and then to the right, Fig. 4, in line with the string for again picking the latter. This swinging movement of the pick is effected by the several cam-surfaces mentioned in opposition to the frictional resistance of the adjacent ends or sections of the actuating-post or pick plunger or actuator.

Briefly stated, the operation of my invention is as follows: The parts being in the position shown in Fig. 2, if it is desired to pick a string the operator places his finger upon the thumb-piece k³ and quickly depresses the same, thereby simultaneously removing the damper k¹³ from contact with the string and at the same time bringing the pick k⁴ in striking engagement with the string a. The pick is not in sliding contact with anything whatever excepting the string when picking the latter; but the moment that it has passed the string it strikes the steep incline k¹⁵ of the cam-surface noiselessly and is deftly swung to the left of said surface by the surface k¹⁶, during which movement the damper k¹³ is further depressed to an extent sufficient to carry it entirely beyond all possibility of influence with the vibrations of the picked string, this movement, however, not being

sufficient to affect said damper with relation to adjacent strings. The operator having permitted the picked string to vibrate the length of time required simply removes his finger from the key, and thereupon the spring k^6 instantly raises the pick and damper actuator, the former being immediately swung back and by the surface k^{17} to the position shown in Fig. 2 and the damper permitted to reengage the string, there being, however, no noise in any of these movements because of the slanting cam-surfaces and because of the felt stop k^{10} , which engages the ear k^9 just as the pick has about reached the top of the surface k^{17} , as shown.

While it has been one aim of my invention to provide a comparatively rigid pick k^4 , which would not be required to yield materially in picking the strings and would not be required to have any spring action or resilient movement for the purpose of avoiding the string when again restored to operative position, yet I do not wish to be restricted in this respect excepting as to those claims where the said feature is incorporated, and I wish it understood also that my main object has been to simplify this kind of device and to produce a device capable of instantaneous movement without uncertainty and with as few and simply-constructed parts as possible.

In accomplishing my purpose it will be seen that I have used simply two posts, or, as it may be termed, a post made in two sections, constituting the pick-actuator, said posts being entirely without complication or peculiar construction and simply maintaining the pick between them and being guided in an ordinary tube provided with a cam-shaped slot or opening through which the pick projects, and it will be seen that the damper is also of the simplest construction, being simply a resilient tube or cushion, and its actuator is equally simple, being merely a depending finger.

I have taken pains to point out the simplicity of my invention, because this very simplicity constitutes the chief merit of my invention, and it has been this simplicity which I have striven to secure.

Having described my invention, what I claim as new, and desire to secure by Letters Patent, is—

1. A pick-key for musical instruments, comprising a pick in the form of a substantially rigid tongue, an actuator for depressing and raising said pick, the latter projecting transversely to the length of the actuator, a guide for said actuator, and means for shifting said pick axially of the actuator out of the path of said string in the upward movement of the pick.

2. A pick-key for musical instruments, comprising a pick in the form of a substantially rigid tongue, an actuator for depressing and raising said pick, a tubular guide within which said actuator moves, and a cam-surface cut in said tubular guide, through which

the pick projects laterally, for shifting said pick out of the path of said string in the upward movement of the pick.

3. A pick-key for musical instruments, comprising a pick-actuator, composed of two parts placed end to end, a pick mounted between said parts and capable of swinging movement, said actuator serving to move said pick up and down, and means for swinging said pick to one side and back again during its up-and-down movement.

4. A pick-key for musical instruments, comprising an actuator made in the form of two post-like members placed end to end, a pick pivotally mounted between the contiguous ends thereof, a spring normally holding said actuator in raised position and maintaining said pick frictionally in place, and a cam co-operating with said pick as moved by said actuator in swinging the pick to one side and back again during the actuation of the pick.

5. A pick-key for musical instruments, comprising a pick, an actuator therefor, and a cam-surface to be engaged by said pick, said actuator carrying said pick down and up, said pick in its downward movement first picking a string and then coming into contact with said cam-surface, and being deflected thereby, the upper end of said cam-surface being steep for preventing noise due to the engagement therewith of said pick.

6. A pick-key for musical instruments, comprising a pick, an actuator therefor, and a cam-surface for moving said pick out of and into operative position as it is actuated by the actuator, said pick being movable freely in its picking operation without sliding contact, and engaging said cam-surface after it has picked a string.

7. A pick-key for musical instruments, comprising an actuator, a pick carried thereby, a guide for said actuator, a cam-opening in said guide, said pick projecting through said opening and being capable of swinging movement relatively to said guide, being swung by engagement with the cam-surface of said opening, said guide having an ear, a pending part carried by said a ear, and moving in said ear to prevent rotation of the actuator, and containing a projection adapted to engage with said ear, and limit the movement of the actuator and pick.

8. A pick-key for musical instruments, comprising an actuator, a pick carried thereby, a cam-surface for swinging said pick laterally and back again, an arm moving with said actuator, a stop extending transversely of said arm and carried thereby for limiting the movement of said actuator, a damper in the form of a resilient tube mounted transversely of the strings beneath said arm and actuated thereby simultaneously with said pick.

9. In a musical instrument, a keyboard, playing-strings mounted in position, a pick-key mounted adjacent a string to pick the same, a damper extending transversely of

and beneath said strings, said damper consisting of a resilient tube, and means operated by said key for depressing said damper and thereby removing it from damping engagement with the string being picked.

10. In a musical instrument, a keyboard, playing-strings mounted in position thereon, a resilient tubular damper extending normally in contact with said strings transversely

thereof, and means for actuating said damper.

In testimony whereof I have signed my name to this specification in the presence of two subscribing witnesses.

JOHN C. ST. JOHN.
